Des. 218,030
Patented July 14, 1970

218,030

ARCHITECTURAL SURFACE COVERING

John S. Ford, St. Louis, Mo., assignor to Monsanto
Co., St. Louis, Mo.

Filed Apr. 12, 1968, Ser. No. 11,446

Term of patent 14 years

Int. Cl. D25—01

U.S. Cl. D18—2

FIG. 1

FIG. 2

FIG. 1 is a perspective view of the architectural surface covering showing my new design, the dotted lines therein being for illustrative purposes only; and

FIG. 2 is a plan view of the repeat unit shown in FIG. 1.

I claim:

The ornamental design for architectural surface covering, substantially as shown and described.
